CASING FOR A SIX MAN WELDING UNIT

Charles H. Stevens, Jr., Cornwall Bridge, Conn., assignor
to C. H. Stevens and Company, Inc., Cornwall Bridge,
Conn., a corporation of Connecticut

Application November 20, 1953, Serial No. 27,687

Term of patent 14 years

(Cl. D26—5)

The single figure is a front perspective view of a casing for a six man welding unit, showing my new design.

The other end of the casing, not seen, is identical with the end that is seen and the back is conventional and covered with the grid-like material shown on the end view disclosed.

The characteristic features of my design for the welding unit disclosed reside in the centrally disposed gable roof and the front panels.

I claim:

The ornamental design for a casing for a six man welding unit, as shown and described.
